UNITED STATES PATENT OFFICE.

CHARLES L. GOODRUM, OF NEW YORK, N. Y., ASSIGNEE TO WESTERN ELECTRIC COMPANY, INCORPORATED, OF NEW YORK, N. Y., A CORPORATION OF NEW YORK.

TELEPHONE-EXCHANGE SYSTEM.

1,244,488.

Specification of Letters Patent. Patented Oct. 30, 1917.

Application filed January 20, 1916. Serial No. 73,217.

To all whom it may concern:

Be it known that I, CHARLES L. GOODRUM, a citizen of the United States, residing at New York, in the county of New York and 5 State of New York, have invented certain new and useful Improvements in Telephone-Exchange Systems, of which the following is a full, clear, concise, and exact description.

This invention relates to telephone exchange systems, wherein a calling line is 10 automatically associated with an idle operator upon the removal of the receiver at the substation thereof.

One of its objects is to provide a circuit 15 arrangement, wherein during light load hours, as for example during the night, all incoming calls may be concentrated upon a particular position, and if the connecting circuits of such position apportioned to a 20 particular line group become busy, to automatically bring about a circuit change which will result in further calls arriving at positions on either side of such night position, so that the night operator can reach over 25 into such positions and answer such calls without arising from her seat.

Another object is to provide a circuit arrangement wherein, when an automatic finder switch is taken for use by a calling 30 line, the position to which such finder belongs will become artificially busy until the operator has performed some act incident to the answering of the call, as for example, depressing her listening key when the idle 35 connecting circuits of such position are again accessible to calling lines.

Referring to the drawings, Figures 1, 2 and 3 illustrate an embodiment of this invention. Fig. 2 should be placed below Fig. 40 1, and Fig. 3 to the right of Fig. 2.

The lines may be divided into groups of say 100 lines each, which terminate in multiples 24, 25 and 26 in a number of automatic 45 finder switches, dependent on the traffic. In an office of 1000 lines, each such group would be multiplied to say ten finders. There would thus be 100 finders. These finders would be distributed among say five operators' positions, each position having two 50 finders from each group of 100 lines. Each of these groups of 100 lines would be divided into subgroups of say ten lines each. The automatic finder switches may be of the type shown in my application, Serial No. 55 872,743, filed November 18, 1914, Automatic

telephone exchange systems. Each subgroup of lines, as shown in such patent, has a finder apportioned thereto; that is to say, one of the sets of brushes 18, 19 and 20 on the shaft 17, is, if such finder is idle, in operative relation to multiples 24, 25, 26 of such subgroup. In case such finder is busy, however, the brush shaft 17 of the next idle finder, containing multiples of the group containing such subgroup and pre-selected by a starter wire, is given a rotary movement by the magnet 28, until the brush 21 engages the grounded multiple segment 16 individual to the calling subgroup on the switch G associated with such finder, at 70 which time a set of brushes 18, 19, 20 on the shaft 17, is in operative relation to multiples 24, 25, 26 of the calling line subgroup, whereupon the brush shaft is given a vertical movement by the magnet 23 to the terminals 24, 25, 26 of the calling line.

10 and 12 designate respectively the line and cut-off relays of substation A, and 60 and 61 the line and cut-off relays of another line in the same subgroup. 200 designates 80 a starting relay which is common to the subgroup to which substation A belongs. Relays 201, 205 and 202 are also common to the lines of this subgroup, and their functions will appear from a detailed description of the operation of the system. Relays 270, 246, 250, 247 and 271 are relays corresponding to relay 200 of other subgroups. The finder is controlled by a side switch, the escapement magnet of which is shown 90 at 22. These switches are well known in the art. Arms 1, 2, 3 (Fig. 1) and 3' (Fig. 2) belong to the side switch of the finder shown in Fig. 1. The remaining side switch arms shown in Fig. 2 belong to the side 95 switches of the finders apportioned to the subgroups under the common relays of which they are shown.

It is believed that the invention will be more readily understood from a detailed description of the operations involved in establishing a connection.

Upon the removal of the receiver by the calling party at substation A, line relay 10 is energized. In attracting its armature, it 105 closes the following locking circuit for itself and relay 200, common to this subgroup. Free pole of battery, left winding of relay 10, left armature and back contact of relay 12, conductor 13, left armature of 110

relay 10, spring 14, conductor 15, left armature and back contact of slow relay 201, relay 200 to ground. Relay 200 locks itself to conductor 215, independent of the left armature and back contact of relay 201. Relay 200 at its right armature and front contact, grounds multiples 16 of the calling line subgroup.

Assuming the finder shown in Fig. 1 normally apportioned to this subgroup to be idle, the brush 21 on the switch G thereof will be in engagement with contact 16 of this subgroup, and a set of brushes 18, 19 and 20 will be in operative relation to multiples 24, 25, 26 of the subgroup containing substation A. Under this assumption, the attraction of the right armature of relay 200 closes the following circuit to move the side switch magnet 22 into position 2, to close the circuit of stepping magnet 23 to elevate brushes 18, 19 and 20 over the terminals 24, 25 and 26 of the calling line subgroup: free pole of battery, armature and back contact of release magnet 27, magnets 28, 22, arm 1 and its first contact, conductor 65, brush 21, contact 16, conductors 28', 228, right armature and front contact of relay 200 to ground. The side switch escapement magnet 22 only, is energized by the closure of this circuit, the stepping magnet 23 remaining inert. Magnet 22 is constructed and arranged to move the side switch from position 1 to position 2, upon its energization. Relay 200, in attracting its right armature, closed the following circuit for a slow relay 202: free pole of battery, relay 202, conductor 203, right armature and front contact of relay 200 to ground. Consequently, when arm 1 of the side switch moves into position 2, the circuit for escapement magnet 22 is maintained energized over the following circuit: free pole of battery, armature and back contact of magnet 27, magnets 28, 22, arm 1 and its second contact, conductor 30, conductor 206, right armature and back contact of relay 205, conductor 212, relay 201, conductor 204, left armature and front contact of relay 202, conductor 203, right armature and front contact of relay 200 to ground. Arm 3 of the side switch, in moving into position 2, closes the following circuit for the stepping magnet 23 to elevate brushes 18, 19, 20 over terminals 24, 25, 26 in search of the calling line: free pole of battery, armature and back contact of magnet 27, magnet 23, arm 3 and its second contact, conductor 29, armature and back contact of magnet 23, conductor 54, armature and front contact of magnet 22, conductors 30, 206, armature and back contact of relay 205, slow relay 201, conductor 204, left armature and front contact of relay 202, conductor 203, to ground at the right armature and front contact of relay 200. The magnet 23 makes and breaks its

own circuit, thus stepping brushes 18, 19, 20 over the multiples 24, 25, 26 of the calling line subgroup in the well-known manner. Relay 201 is slow-acting, and consequently its left armature maintains open the circuit of release magnet 27 until it is opened at another point by the attraction of the left armature of answering supervisory relay 32 when the calling line is found.

Arm 2 in position 2, connects ground to test brush 20 by way of conductor 30. As the brush 20 wipes over the test multiples 26, the relays 12 are energized in succession. When the cut-off relay of the calling line is energized, in attracting its left armature it opens the locking circuit of relay 10, which circuit includes relay 200. Relay 200, in retracting its right armature, removes ground from conductor 30 in the circuit of stepping magnet 23, thus stopping the finder, and also deenergizes magnet 22 and relay 202. Relay 10 in closing contacts 14 and 66, restores the control of starter wire 15 to the remaining lines of the subgroup to which substation A belongs. Magnet 22 is constructed and arranged to move the side switch from position 2 to position 3, upon its deenergization. In position 3, arm 2 connects ground to the cut-off relay 12, to maintain such cut-off relay energized until the connection is disestablished. Arm 3 in position 3, extends the starter wire to the next idle finder having multiples of this line group. Answering supervisory relay 32 is now energized over the following circuit: free pole of battery, left winding of relay 32, conductors 33 and 34, brush 19, terminal 25, line conductor *a*, through the telephonic apparatus at substation A, line conductor *b*, terminal 24, brush 18, conductors 35, 36, right winding of relay 32 to ground. Relay 32, by attracting its right armature, interposes a break in the circuit of answering supervisory lamp 37, and by attracting its left armature, interposes a break in the circuit of release magnet 27, and closes the following circuit for lamp 38, to indicate to the operator the arrival of a call: ground, armature and back contact of relay 39, conductor 40, left armature and front contact of relay 32, conductor 41, lamp 38, contacts 42, 43 of listening key LK, conductors 44, 207, 300, 301, relay 318, free pole of battery. The operator now depresses her listening key LK, and ascertains the number of the wanted subscriber. Contacts 42, 43 in opening, extinguish lamp 38. She then, by means of the plug P, tests the called line in the well-known manner, and if idle, inserts plug P in the jack J thereof. The engagement of the sleeve of the plug P with the sleeve of the jack J, energizes cut-off relay 46 of the called line and relay 39. Relay 39, in attracting its armature, lights calling supervisory lamp 47. The operator now actuates 130

ringing key RK, connecting ringing generator 48 with the called line, to ring the bell *e* thereat. When the calling party responds, calling supervisory relay 45 is energized, and opens the circuit of lamp 47. Talking current is fed to substation A over the windings of answering supervisory relay 32, and to substation B over the windings of calling supervisory relay 45, in the well-known manner. When the subscribers replace their receivers, these relays become deenergized and the supervisory lamps 37 and 47 become lighted, whereupon the operator pulls out the P plug from the jack J. Relay 39 and cut off relay 46 thereupon become deenergized. Relay 39 in closing its back contact, closes the circuit of release magnet 27 of the finder as follows: free pole of battery, magnet 27, conductor 49, conductor 208, right armature and back contact of relay 201, conductor 209, conductor 50, off normal contact 51 of the finder, conductor 52, left armature and back contact of relay 32, conductor 40, armature and back contact of relay 39 to ground. The release magnet 27 thereupon becomes energized and withdraws the holding pawls from the brush shaft in the well-known manner, whereupon the switch is restored by gravity.

It will be noted that the call just traced, involving substation A, led through a connecting circuit at position 3; that is to say, the calls from the subgroup of lines to which relays 200, 201, 205 and 202 are common, are normally answered by the operator at position 3. It is to be understood that the finder shown in Fig. 1 is the finder normally apportioned to this particular subgroup of lines; that is to say, a set of brushes 18, 19 and 20 on this finder brush rod, normally rest in operative relation to multiples 24, 25, 26 of this subgroup. It will be also understood, however, as previously pointed out, that any given finder has access to a hundred lines made up of ten subgroups of ten each, and in case the finder normally apportioned to any particular subgroup is busy when a call is initiated in such subgroup, a finder preselected by the extended starter wire and containing multiples of the group containing the calling subgroup, will be started in motion upon the initiation of such call, and its brush shaft 17 will be given a rotary movement to pick out the calling subgroup multiple contact 16 on its switch G, and thereafter a vertical movement to cause the positioned set of brushes to pick out the calling line in the subgroup.

Assume now that all the operators leave their positions, except operator No. 1. In such event, plugs 302, 303 of the head-set of operator No. 2 are withdrawn from the jacks 304, 305, and the plugs 306, 307 of the head-set of operator No. 3 are withdrawn from jacks 308, 309, and similarly

the plugs of the other operators. The withdrawal of plug 302 from jack 304 grounds conductor 310, and the withdrawal of plug 306 from jack 308 grounds conductor 311. Relays 210, 211, bridged off conductor 310, 70 one for each subgroup normally served by this operator, are energized upon the grounding of such conductor. Relays 205 and 313, bridged off conductor 311, one for each subgroup normally served by this operator, are 75 energized by the grounding of this conductor.

Corresponding relays of the other operators are also energized upon the removal of their head sets. All incoming calls will 80 now be concentrated upon the connecting circuits terminating at position 1. For example, assume a call originates in the subgroup to which relay 200 is individual, and which is normally served by the operator 85 at position 3. The initiation of such call energizes relay 200 as described. Relay 200, by attracting its right armature, closes the following circuit to start an idle finder terminating at position 1, which is assumed to 90 be the right position: ground, right armature and front contact of relay 200, conductor 203, relay 202 to free pole of battery. Relay 202 in attracting its left armature, extends this ground over conductor 204, relay 201, conductor 212, armature and front contact of relay 205 (now energized), conductor 213, left armature and back contact of relay 216 of a subgroup normally answered by the operator at position 2, relay 95 217, conductor 218, armature and front contact of relay 211 (now energized), conductor 219, conductor 220, left armature and back contact of relay 221, conductor 222, relay 223, conductor 224, armature and back contact of relay 225, (now inert) conductor 226 leading to the primary stepping magnet corresponding to 28 of a finder in which one of the connecting circuits terminates at position 1, which has access to the group 100 containing the calling subgroup. Assume the finder shown in Fig. 1 to be such finder. The circuit continues as follows: conductor 226, conductor 30, conductor 53, armature and back contact of stepping magnet 28, conductor 54, armature and back contact of stepping magnet 23, conductor 29, arm 3, and its first contact, conductor 55, rotary stepping magnet 28, conductor 56, armature and back contact of release magnet 27, to the free 105 pole of battery. Stepping magnet 28 makes and breaks its own circuit, thus rotating brush 21 of the switch G. When such brush engages the multiple contact 16 of the calling line subgroup on the switch G, the following circuit is closed to stop the rotary movement of the finder, at which time a set of brushes 18, 19, 20 on the finder shaft 17 is in 110 operative relation to multiples 24, 25, 26 of the calling line subgroup; free pole of bat- 115

tery, armature and back contact of magnet 27, conductor 56, magnet 28, side switch escapement magnet 22, side switch arm 1 and its first contact, conductor 65, brush 21, contact 16, conductors 28', 228, to ground at the right armature and front contact of relay 200. Escapement magnet 22 by moving the side switch into position 2, opens the stepping circuit traced. In position 2, the following circuit is closed to maintain magnets 22, 28 energized: free pole of battery, armature and back contact of magnet 27, conductor 56, magnets 28, 22, arm 1 and its second contact, conductor 30, conductor 226 to ground at the right armature and front contact of relay 200 over the circuit previously traced.

In position 2 the stepping magnet 23 is energized over the following circuit: free pole of battery, armature and back contact of magnet 27, magnet 23, arm 3 and its second contact, conductor 29, armature and back contact of magnet 23, conductor 54, armature and front contact of escapement magnet 22, conductor 30, conductor 226 to ground at the right armature and front contact of relay 200, over the circuit previously traced. The stepping magnet 23 makes and breaks its own circuit thus causing the set 30 of brushes 18, 19, 20 so positioned to wipe over the multiples 24, 25, 26 of the calling line subgroup. When the test brush 20 reaches the test terminal 26 of the calling line, the cut-off relay 12 thereof is energized, and by attracting its left armature, opens the locking circuit for relay 200 which in turn, by retracting its right armature, releases relay 202 and removes ground from the conductor 226, thus opening the circuit 35 of magnets 23, 22 and 28. The escapement magnet 22 in deenergizing, allows the side switch to move to position 3, in which position arm 2 grounds the test brush 20 to hold the cut-off relay 12 energized until the 40 establishment of the connection. From this point on, the operations are the same as previously described, the lamp 38 lighting upon the energization of relay 32 of such cord circuit, to indicate the arrival of the 45 call at position 1.

Assume now that during the establishment of the connection just traced, a call is initiated in a subgroup of lines normally served by the operator at position No. 2 50 to which subgroup relay 250 is common. Relay 250 is energized, and by attracting its right-armature, closes the following circuit to start a finder at the position of operator No. 1: ground, right armature and 55 front contact of relay 250, conductor 227, relay 216, free pole of battery. Relay 216, by attracting its left armature, extends this ground to conductor 228', relay 217, right armature and front contact of relay 211, 60 conductors 219, 220, left

armature and back contact of relay 221, conductor 222, relay 223, conductor 224, right armature and back contact of relay 225, conductor 226, conductor 30, conductor 53, armature and back contact of magnet 28, conductor 54, armature and back contact of magnet 23, conductor 29, arm 3 of the side switch and its third contact, conductor 58, conductor 229, left armature and back contact of relay 230, conductor 231, relay 232, conductor 260, armature and front contact of relay 313 (now energized), conductor 233, left armature and back contact of relay 234, conductor 235, relay 236, conductor 237, armature and front contact of relay 210 (now energized), conductor 238, conductor 239, left armature and back contact of relay 240, conductor 241, relay 242, conductor 243, armature and back contact of relay 244 (now inert), conductor 245, conductors 30 and 53 of the finder normally serving the subgroup to which relay 246 belongs, armature and back contact of magnet 28 thereof, conductor 54, armature and back contact of magnet 23, conductor 29, arm 3 and its first contact, conductor 55, magnet 28, conductor 56, armature and back contact of magnet 27, free pole of battery. The stepping magnet 28 of such finder makes and breaks its own circuit, thus stepping the brush 21 around 55 in search of the calling line subgroup contact.

When the brush 21 engages such contact, the following circuit is closed to move the side switch into position 2, to terminate the 100 rotary movement of the brush shaft and begin the vertical movement thereof: free pole of battery, armature and back contact of magnet 27, conductor 56, magnets 28, 22, arm 1, conductor 65, brush 21, multiple contact 16, conductor 28', conductor 251, ground at the right armature and front contact of relay 250. The escapement magnet 22, in energizing, moves the side switch into position 2, in which position magnets 28, 22 are 110 maintained energized over the following circuit: free pole of battery, armature and back contact of magnet 27, conductor 56, magnets 28 and 22, arm 1, conductor 30, conductor 245, armature and back contact of 115 relay 244, conductor 243, relay 242, conductor 241, left armature and back contact of relay 240, conductors 239, 238, armature and front contact of relay 210, conductor 237, relay 236, conductor 235, left armature 120 and back contact of relay 234, conductor 233, armature and front contact of relay 313, conductor 260, relay 222, conductor 231, left armature and back contact of relay 230, conductor 229, conductor 58 (Fig. 1), arm 125 3 and its 3rd contact, conductor 29, conductor 54, armature and back contact of magnet 28, conductor 53, conductor 30, conductor 226 (Fig. 2), armature and back contact of relay 225, conductor 224, relay 223, 130

conductor 222, left armature and back contact of relay 221, conductor 220, conductor 219, armature and front contact of relay 211, conductor 218, relay 217, conductor 5 228, left armature and front contact of relay 216, conductor 227 to ground at the right armature and front contact of relay 250. In position 2 the side switch arm 3 closes the following circuit for vertical stepping 10 magnet 23 in parallel with that just traced: free pole of battery, armature and back contact of magnet 27, conductor 56, magnet 23, arm 3, conductor 29, armature and back contact of magnet 23, conductor 54, armature and front contact of magnet 22, conductor 30, conductor 245, to ground at the right armature and front contact of relay 250 over the circuit just traced. The magnet 23 makes and breaks its own circuit, 15 thus elevating the brushes 18, 19 and 20 over the multiples 24, 25 and 26 of the calling subgroup. In position 2, arm 2 connects ground to the test brush 20. Thus, as the finder brushes are elevated, the cut-off relays 12 are energized in succession. When the cut-off relay 12 of the calling line is reached, in attracting its left armature it opens the locking circuit including the line 20 relay of the calling line and relay 250. Relay 250, in retracting its right armature, removes ground from the circuit traced for magnets 23, 28 and 22. The magnet 22 in deenergizing, allows the side switch to move into position 3. The answering supervisory 25 relay 32 of the cord circuit at operator's position No. 1 becomes energized when brushes 18, 19 engage terminals 24 and 25 of the calling line; and by attracting its left armature, lights the lamp 38 thereof, 30 to indicate to the operator at position No. 1 the arrival of a call. From this point on the operation is the same as that previously traced.

Side switch arm 1¹, shown in Fig. 2, begins 45 longs to the line finder normally serving the subgroup to which relay 246 belongs; and side switch arm 1² belongs to the side switch of the finder normally serving subgroup to which relay 247 belongs. When 50 these two finders are taken for use, which are the only ones at position 1 which contain multiples of the same group of 100 lines, other calls from this group cannot be answered at position 1. When the finder 55 side switches of these finders move into position 3, however, the following circuit is closed for relay 314, individual to position 1: free pole of battery, relay 314, conductors 315, 316, conductor 248, side switch 60 arms 1² and 1¹, to ground. Relay 314, by attracting its left armature, removes ground from conductor 311, from which conductor relays 313, 205 of subgroups normally served by operator No. 3 are bridged. Consequently, 65 these relays in retracting their

armatures, restore the connection of the finders of position 3 with the starting circuit, so that calls may come in on such finders. This position being adjacent to the position of operator No. 1, such operator 70 can reach over without getting up from her chair, and take care of the calls.

Assuming now that both the finders at 75 positions 3, serving a given group of 100 lines, become busy. In such event the side switch arms 3¹, 3² thereof, in series in conductor 249, are in the third position. This causes the closure of the following circuit for relay 318 at the position of operator No. 3: free pole of battery, relay 318, conductors 301 and 249, side switch arms 3², 3¹, to ground. Relay 318 by attracting its left armature, removes ground from conductor 310; thus deenergizing relays 210, 211, which restore the connection of the finders of position 2 with the starting circuit so that calls may come into the finders of this position, which is on the other side of the right position. In this case, as before, the operator at position No. 1 can reach over, without getting up from her chair, and take care of subsequent calls which may be initiated in any of the groups.

Referring back to that point in the operation of the system where the finder arrives 95 on the calling line terminals and the answering supervisory relay 32 operates, the attraction of the left armature of relay 32, energizes relay 318 over the circuit previously traced, which circuit leads as follows:—free 100 pole of battery, relay 318, conductors 301, 300, 207, 44, contacts 42, 43 of the operator's listening key LK, lamp 38, left armature and front contact of relay 32, conductor 40 to ground at the armature and back contact of relay 39. Relay 318, in attracting its armature, grounds conductor 311, which energizes relays 313, 205, etc., of the subgroups of lines normally served by this operator.

It will be apparent from what has gone before that incoming calls cannot start finders of connecting circuits terminating at this operator's position as long as relay 318 remains energized. This relay remains energized until the listening key LK of the cord upon which the call is awaiting, is actuated. It then becomes deenergized by the opening of contacts 42, 43 of the listening key, and its armature in retracting, deenergizes relays 205, 313, etc., thus restoring the normal connection of the starting circuit with these finders so that a subsequent incoming call can start the preselected one in motion.

A pilot relay 320 is provided adapted to be energized when the relays 318, 314, etc., are simultaneously energized. This relay controls a pilot lamp 321 to indicate when all the operators are busy.

What is claimed is:

1. In a telephone exchange system, the combination with telephone lines divided into groups, a group of connecting circuits for each of said line groups, operators' positions among which said connecting circuits are distributed in such a manner that some of the connecting circuits serving each line group appear at each position, means for automatically associating said connecting circuits with calling lines upon the initiation of calls therein, and means for rendering all said positions except one artificially busy and for concentrating calls on the connecting circuits of such position, of means operating automatically when the connecting circuits of a given group at such position become busy for removing the artificial busy condition of the connecting circuits at an adjacent position.
2. In a telephone exchange system, the combination with telephone lines divided into groups, a group of connecting circuits for each of said line groups, operators' positions among which said connecting circuits are distributed in such a manner that some of the connecting circuits serving each line group appear at each position, means for automatically associating said connecting circuits with calling lines upon the initiation of calls therein, and means for rendering said positions artificially busy and for concentrating calls from said line groups on the connecting circuits of a particular position, of means operating automatically when the connecting circuits of a given group at such position become busy for removing the artificial busy condition of the connecting circuits at an adjacent position, and means operating automatically when the connecting circuits of such group at such adjacent position become busy for removing the artificial busy condition of the other adjacent position.
3. In a telephone exchange system, the combination with telephone lines, connecting circuits terminating in automatic finder switches to which said lines are multiplied in groups, operators' positions among which said connecting circuits are distributed in such a manner that some of the connecting circuits serving each group appear at each position, means for causing one of said finders to connect with a calling line upon the initiation of a call therein, means for rendering said positions artificially busy and for concentrating all calls on the connecting circuits of a particular position, and means operating automatically when the connecting circuits of a given line group at such position become busy for removing the artificial busy condition of the finders at an adjacent position.
4. In a telephone exchange system, the combination with telephone lines, connect-

ing circuits terminating in automatic finder switches to which said lines are multiplied in groups, operators' positions among which said connecting circuits are distributed in such a manner that some of the connecting circuits serving each group appear at each position, means for causing one of said finders to connect with a calling line upon the initiation of a call therein, means for rendering said positions artificially busy and for concentrating all calls on the connecting circuits of a particular position, means operating automatically when the connecting circuits of a given group at such position become busy for removing the artificial busy condition of the finders at an adjacent position, and means operating automatically when the connecting circuits of such group at such adjacent position become busy for removing the artificial busy condition of the other adjacent position.

5. In a telephone exchange system, the combination with telephone lines, connecting circuits terminating in automatic finder switches to which said lines are multiplied in groups, side switches controlling said finders, operators' positions among which said connecting circuits are distributed in such a manner that some of the connecting circuits serving each group appear at each position, means for causing one of said finders to connect with a calling line upon the initiation of a call therein, means for rendering said positions artificially busy and for concentrating all incoming calls on the connecting circuits of a particular position, and a circuit adapted to be closed when the side switches of the finders of a given group at such position are off normal for removing the artificial busy condition of the finders at an adjacent position.

6. In a telephone exchange system, the combination with telephone lines, connecting circuits terminating in automatic finder switches to which said lines are multiplied in groups, operators' positions among which said connecting circuits are distributed in such a manner that some of the connecting circuits serving each group appear at each position, means for causing one of said finders to connect with a calling line upon the initiation of a call therein, and means for concentrating all incoming calls on the finders of a particular position.

7. In a telephone exchange system, the combination with telephone lines, connecting circuits terminating in automatic finder switches to which said lines are multiplied in groups, operators' positions among which said connecting circuits are distributed in such a manner that some of the connecting circuits serving each group appear at each position, a starter wire adapted to preselect an idle finder, and means for changing the normal relation of said starter wire to said

finders so that all incoming calls will be concentrated upon the finders of a particular position.

8. In a telephone exchange system, the combination with telephone lines divided into groups, each of said groups being divided into subgroups, automatic finder switches to which said lines are multiplied, there being provided as many finders for each group as there are subgroups therein, and each subgroup having a finder apportioned thereto with a set of brushes in operative relation to multiples thereof, a relay (200, 271) for each subgroup, a starter wire controlled thereby, and normally associated with the finder apportioned thereto, a second relay (205, 313) for each subgroup, groups of connecting circuits for said line groups adapted to be associated with said lines by said finders, operators' positions including a night position, said connecting circuits being distributed among said positions in such a manner that some of the connecting circuits serving each group appear at each position, means including manual switches at said positions for operating said relays (205, 313) to transfer the starter wires from operative relation to their associated finders and into operative relation with an idle connecting circuit at said night position.

9. In a telephone exchange system, the combination with telephone lines divided into groups, each of said groups being divided into subgroups, automatic finder switches to which said lines are multiplied, there being provided as many finders for each group as there are subgroups therein, and each subgroup having a finder apportioned thereto with a set of brushes in operative relation to multiples thereof, a relay (200, 271) for each subgroup, a starter wire controlled thereby and normally associated with the finder apportioned thereto, a second relay (205, 313) for each subgroup, groups of connecting circuits for said line groups adapted to be associated with said lines by said finders, operators' positions including a night position, said connecting circuits being distributed among said positions in such a manner that some of the connecting circuits serving each group appear at each position, a head-set at each position, a plug and jack by means of which said set is placed in operative relation to the connecting circuits of its position, means operated by the withdrawal of said plugs for operating said relays (205, 313) to transfer the starter wires from operative relation to their associated finders and into operative relation with an idle connecting circuit at said night position.

10. In an automatic telephone exchange system wherein the calling lines are divided into groups, the groups terminating in dif-

ferent sections of a row of terminals multiplied so as to be accessible to a number of brush carriers, the combination with a carrier for each row, driving means for said carriers, multiply connected brushes mounted on said carriers one for each section of terminals, means associated with said carriers and so constructed and arranged that upon the simultaneous initiation of calls in several of said groups, brushes, each serving a different section will be simultaneously driven over such sections by said driving means in search of the calling lines, a connecting circuit associated with each carrier, operators' positions among which said connecting circuits are distributed in such a manner that some of the connecting circuits serving each group appear at each position, means for automatically rendering the position to which an actuated carrier belongs artificially busy, and manual means controlled by the operator in answering a call for removing such artificial busy condition.

11. In a telephone exchange system where-in calling lines are divided into groups and terminate in a row multiplied across the face of a panel, the combination with a carrier for each row, multiply connected brushes mounted spirally upon each carrier one for each group of terminals, the carriers being so arranged that each group of lines has a brush normally in operative relation to multiples thereof, means for moving said carriers independently upon the initiation of calls in said groups, a connecting circuit associated with each carrier, operators' positions among which said connecting circuits are distributed in such a manner that some of the connecting circuits serving each group appear at each position, means for causing one of said finders to connect with a calling line upon the initiation of a call therein, means for thereupon automatically rendering the position to which said carrier belongs artificially busy, and manual means controlled by the operator in answering a call for removing such artificial busy condition.

12. In a telephone exchange system, the combination with telephone lines divided into groups, a group of connecting circuits for each of said line groups, operators' positions among which said connecting circuits are distributed in such a manner that some of the connecting circuits serving each line group appear at each position, means for automatically associating said connecting circuits with calling lines upon the initiation of calls therein, and means for rendering certain of said positions artificially busy and for concentrating calls from a plurality of line groups upon the connecting circuits of a particular position, of means operating automatically when a given number of the connecting circuits of a given line group at

such position become busy for removing the artificial busy condition of the connecting circuits at an adjacent position.

13. In a telephone exchange system, the combination with telephone lines divided into groups, a group of connecting circuits for each of said line groups, operators' positions, among which said connecting circuits are distributed in such a manner that some 10 of the connecting circuits serving each line group appear at each position, automatic switch for associating said connecting circuits with calling lines upon the initiation of calls therein, a starter wire, relays (205, 15 313) for controlling the same, means includ-

ing a manual switch at each position for operating the relays (205, 313) thereof to transfer the starter wire from operative relation to the automatic switches of such position and into operative relation with an 20 idle connecting circuit of another position, a relay (318) operated upon the initiation of a call and adapted to operate said relays (205, 313) and a listening key adapted when actuated by the operator to deenergize said 25 relay (318).

In witness whereof, I hereunto subscribe my name this 19th day of January, A. D. 1916.

CHARLES L. GOODRUM.
